(57) **CLAIM**

The ornamental design for a receptacle with collection structure, as shown and described.

DESCRIPTION

FIG. 1 is a top view of a receptacle with collection structure showing my new design;

FIG. 2 is a left side view thereof;

FIG. 3 is a left side thereof showing the lid in a closed configuration;

FIG. 4 is a rear view thereof; and,

FIG. 5 is an exploded view thereof.

The broken line showing of the body of a receptacle is included for the purpose of illustrating environment and forms no part of the claimed design.
